[57] CLAIM

The ornamental design for an ice hockey rink insert for a table, as shown and described.

DESCRIPTION

FIG. 1 is a perspective view of an ice hockey rink insert for a table, showing my new design; and

FIG. 2 is a bottom perspective view thereof.

The broken line showing of the top of the table having a recessed portion is for illustrative purposes only, and forms no part of the claimed design.
